(57) CLAIM

The ornamental design for a plug-in head of cord keeper, as shown and described.

DESCRIPTION

FIG. 1 is a perspective view of a plug-in head of cord keeper;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof;
FIG. 7 is a bottom plan view thereof; and,
FIG. 8 is a front elevational view thereof, showing the outlet cover holder and the back piece detatched;
FIG. 9 is a rear elevational view thereof, showing the outlet cover holder and the back piece detatched;
FIG. 10 is a right-side elevational view thereof, showing the outlet cover holder and the back piece detatched;
FIG. 11 is a left-side elevational view thereof, showing the outlet cover holder and the back piece detatched;
FIG. 12 is a bottom plan view thereof, showing the outlet cover holder and the back piece detatched; and,
FIG. 13 is a top plan view thereof, showing the outlet cover holder and the back piece detatched.
The broken lines shown represent unclaimed subject matter and form no part of the claimed design.
